(57) **CLAIM**

What is claimed is the ornamental design for a tailgate light, as shown and described.

DESCRIPTION

FIG. 1 is a right front upper perspective view of the tailgate light.

FIG. 2 is a left rear bottom perspective of the tailgate light of FIG. 1.

FIG. 3 is a top view of the tailgate light of FIG. 1.

FIG. 4 is a front elevation view of the tailgate light of FIG. 1.

FIG. 5 is a bottom view of the tailgate light of FIG. 1; and,

FIG. 7 is a left end elevation view of the tailgate light of FIG. 1, the right end elevation view being a mirror image thereof.
